UNITED STATES PATENT OFFICE.

ARTHUR MIDDLETON ROSE, OF YONKERS, ASSIGNOR TO THE W. & J.
SLOANE, OF NEW YORK, N. Y.

DESIGN FOR CARPET-BODY.

SPECIFICATION forming part of Design No. 24,462, dated July 2, 1895.

Application filed June 1, 1895. Serial No. 551,411. Term of patent 3½ years.

To all whom it may concern:

Be it known that I, ARTHUR MIDDLETON ROSE, a citizen of the United States, residing at Yonkers, county of Westchester, State of New York, have invented and produced a new and original Pattern for a Carpet-Body to be Wrought in Woven Fabric—as, for example, in Wilton carpeting—in such colors as may be desired, of which the following is a specification.

In the accompanying drawing, which forms a part of this specification, the characteristic features consist in the pattern, which shows

rococo figures interspersed with white flowers on a background of uniform color, which is indicated by closely-drawn vertical lines.

What I claim, and desire to secure by Letters Patent of the United States, is—

The design for a carpet body, substantially as shown.

Signed by me, in New York city, this 29th day of May, 1895.

ARTHUR MIDDLETON ROSE.
